UNITED STATES PATENT OFFICE.

AXEL A. STROM, OF AUSTIN, ASSIGNOR TO THE STROM MANUFACTURING COMPANY, OF CHICAGO, ILLINOIS.

RAILROAD-SWITCH APPLIANCE.

SPECIFICATION forming part of Letters Patent No. 438,120, dated October 7, 1890.

Application filed March 10, 1890. Serial No. 343,291. (No model.)

To all whom it may concern:

Be it known that I, AXEL A. STROM, a citizen of the United States, residing at Austin, in the county of Cook and State of Illinois, 5 have invented a new and useful Improvement in Railroad-Switch Appliances, of which the following is a specification.

My invention relates to an improved construction of the connecting means between a 10 railroad-switch and its switch-stand.

The object of my improvement is to provide a construction of connecting-bar and crank on a switch-stand spindle which, while it will permit the bar and crank to be readily 15 connected and disconnected by proper manipulation of the bar for the purpose, will tend to prevent accidental or unintentional separation thereof.

In the accompanying drawings, Figure 1 is 20 a perspective view of a switch-stand having the crank-arm on its rotary spindle adapted to receive a switch-bar of peculiar construction; and Fig. 2, a broken sectional view showing the flaring form of the opening in the 25 crank and the switch-bar inserted into it, the manner of adjusting the switch-bar in applying it to or disconnecting it from the crank being indicated by dotted lines.

A is the switch-stand, of any desired form 30 and construction, employing a vertically-disposed spindle B.

D is the crank-arm, extending horizontally from the spindle near its lower end and provided with an opening o, flaring, as shown 35 at o', downward from the inner side of the opening.

C is the connecting-bar, bent to a right angle at one end to form a lateral extension r, and provided at the extremity of the bent portion r with a toe q.

To connect the bar C with the crank, it is tipped to enter the toe first into the opening o, as indicated in Fig. 2, and by then lowering the bar to the horizontal position (shown by full lines in that figure) and fastening the 45 opposite end in any suitable manner to a switch-rail (not shown) the bar cannot be displaced or removed without first disconnecting it at the switch, when it must be raised from that end to permit its separation from the 50 crank-arm to be effected. The opening o being only large enough at its upper end to admit the lateral extension r of the rod C, the latter when in position prevents the entrance of said and other foreign matter into the opening which would tend to produce rapid wear 55 and impairment of the connection.

What I claim as new, and desire to secure by Letters Patent, is—

In combination with a switch-stand A, having a vertical rotary spindle B, a crank-arm D, extending from the spindle near its lower end and provided with a downwardly-flaring opening o, and a switch-connecting bar C, provided at one end with a lateral extension 60 r, terminating in a toe q and adapted to fit the said flaring opening in the crank-arm, substantially as and for the purpose set forth.

AXEL A. STROM.

In presence of—

J. W. DYRENFORTH,
M. J. FROST.
